UNITED STATES PATENT OFFICE.

ALFRED F. McCOLLUM, OF BLOOMSBURG, PENNSYLVANIA, ASSIGNOR OF THREE-FIFTHS
TO JAMES MAGEE, 2d, OF BLOOMSBURG, PENNSYLVANIA.

BOBBIN-WINDER.

1,317,515.

Specification of Letters Patent. Patented Sept. 30, 1919.

Application filed October 3, 1917. Serial No. 194,612.

To all whom it may concern:

Be it known that I, ALFRED F. McCOLLUM, a citizen of the United States, residing in Bloomsburg, Columbia county, State of 5 Pennsylvania, have invented Bobbin-Winders, of which the following is a specification.

One object of my invention is to provide a bobbin winding machine with novel means for supporting and holding a bobbin spool 10 in such manner that this may be thrown by a single movement from an inoperative to an operative position in engagement with a driving pulley, instead of requiring to be lowered and then locked in its working position as has hitherto been necessary.

I also desire to provide a bobbin winder with a novel device for automatically releasing and throwing up a spindle or spool when this has been filled with a predetermined amount of thread or yarn;—the invention contemplating a novel relation of the spindle with the parts which normally held it in a working position.

I further desire to provide a novel form 25 of bobbin holder which will serve as a brake to prevent rotation of a full bobbin after this has been thrown from a working to an inoperative position and that in spite of the continued operation of the machine.

These objects and other advantageous ends 30 I secure as hereinafter set forth, reference being had to the accompanying drawings, in which,—

Figures 1 and 2 are respectively a front 35 and end elevation of a machine embodying the novel features of my invention;

Fig. 3 is a full sized plan of the bobbin holding and actuating mechanism;

Fig. 4 is a vertical section on the line 4—4, 40 Fig. 3;

Fig. 5 is a fragmentary end elevation of the parts for holding the free end of the bobbin spindle;

Fig. 6 is a horizontal section on the line 45 6—6, Fig. 4, showing the attaching means for the bobbin holding lever;

Fig. 7 is a section on the line 7—7, Fig. 3;

Fig. 8 is an end elevation of a part of the structure shown in Fig. 7;

Fig. 9 is a fragmentary side elevation, 50 showing certain of the parts of Fig. 5 in the positions occupied when the bobbin spindle is released;

Fig. 10 is a section on the line 10—10, 55 Fig. 3;

Figs. 11 and 12 are respectively a side and an end elevation of a slightly modified form of the holding means for the free end of the bobbin spindle.

In the above drawings, 1 and 2 represent 60 a pair of standards connected at the top by a transverse table or plate 3, from the center of which depends a bracket or hanger 4. The lower end of this latter provides bearings 9 for a pair of spindles 5 and 6, whose 65 opposite ends are carried in bearings 7 and 8, supported by or formed as part of the two standards 1 and 2. These spindles in turn support tubes *x* on which is wound the yarn or thread of a pair of supply bobbins *x' x'*. The bearings 7, 8 and 9 are so formed as to permit of the convenient insertion and removal of the spindles 5 and 6. 70

Projecting upwardly from the plate 3 of 75 the frame of the machine are a pair of parallel, vertical standards 24 and 25, providing bearings for a horizontal spindle 26, on which is mounted a fixed pulley 27, although obviously any other suitable driving means may be employed for said spindle. 80 Adjacent the outer faces of the two standards 24 and 25 there are fixed to the spindle 26 a pair of leather covered driving rollers or pulleys 29 and 30, over each of which extends a framework consisting of a rod 31, a bar 32 preferably parallel to said rod and having its ends 33 turned at right angles and a second rod 34 extending between the extremities of said ends, parallel to the rod 31. This latter with the bar 32 is rigidly 90 fixed to the standards 24 and 25 which also provide bearings for a longitudinally slideable rod 35, which at each end has fixed to it a head 36 carrying a thread guide 37. The rod 34 has fixed to it, opposite each of 95 the rollers 29 or 30, a porcelain or other smooth hard thread guide 38.

Each end of the rod 31 has loosely mounted on it a movable frame consisting of a pair of substantially parallel arms 39 and 40 100 engaging said rod and rigidly connected to or integral with a member 41 extending at right angles to them. This member projects beyond the arm 40 and is forked to provide bearings 42 and 43 (Fig. 7) for a 105 short spindle 44 to one of whose ends is fixed a collar 45 and an arm 46 constituting an operating handle.

The collar 45 has projecting radially from it a bobbin spindle 47 and the short spindle 110

44 is acted on by a spring 48 mounted on it between the bearings 42 and 43, in such manner that it tends to turn into a position in which the bobbin spindle is elevated at an 5 angle of about 60° to the horizontal. For limiting this movement, however, I provide a transverse pin 49 in the rear end of the spindle 44 and also a pin 50 projecting rearwardly from the bearing 42, in position to 10 be engaged by said pin 49 when the bobbin spindle occupies its desired elevated position.

The arm 39 of this spindle-carrying frame projects forwardly beyond the member 41 and the underside of its front extremity has 15 a transverse recess 51, Fig. 9, so as to be capable of receiving the free end of the bobbin spindle 47, although it is to be particularly noted that this latter is so set in the collar 45 or is otherwise so supported 20 that it normally tends to occupy a position on the forward side of the line of said recess. Said movable frame has fixed to it on or adjacent the arm 39 a plate 52 downwardly and forwardly curved to one side 25 of and below the recess 51, beyond which it projects for a distance sufficient to engage and limit the downward movement of the bobbin spindle 47.

The bar 32 is preferably, though not necessarily, of rectangular section and has a straight edge extending immediately adjacent and parallel with the cylindrical surface of the driving rolls 29 and 30 which are preferably covered with leather or other 35 equivalent material having a comparatively high coefficient of friction. A flat face of this bar extends outwardly from the surface of each of said rolls and on it, opposite the end of the arm 39, I mount an inverted 40 U-shaped body of strip material 53, Fig. 5, designed to guide the end of the bobbin spindle under the extremity of said arm and to retain it in the recess thereof under 45 normal conditions, when it is lowered as hereafter explained.

A knife blade 54 is preferably mounted on the rod 32 and for the sake of convenience I have shown it as held in place by the same bolt 55 which retains the guide 50 piece 53 in position. It may be noted that if desired, said blade or its supporting structure may be utilized as shown in Figs. 11 and 12, to perform the functions of the guide and retaining piece 53, since such a blade 55 56 may be mounted on the standard 25 adjacent the end of the arm 39 and the plate 52 so as to serve to direct the bobbin spindle under the extremity of said arm as well as to retain it in the recess thereof when the 60 spindle is lowered.

For automatically causing raising of the frame 39-40-41 and freeing the bobbin spindle so that it may move to its elevated position under the action of the spring 48, I 65 form on said arm 40 a downwardly project-

ing finger 57 and adjustably mount on the standard 24 a substantially horizontal lever 58 having one of its arms formed with a wedge-shaped lug 59 placed to coact with said finger. 70

For supporting this lever I provide the standard 24 with a horizontal slot 60 and into this slidably extend the pivot or fulcrum bolt 61 on which said lever 58 is mounted, adjusting the bolt in the slot by a 75 pair of screws 62 and 63, and thereafter clamping it in a given position by its nut 64. The second arm of the lever 58, (which is preferably of the first order) has its upper face formed with a series of notches or teeth 80 65 for the reception of one end of a coil spring 66, whose opposite end is connected to the standard 24 by a bolt or pin 67 so as to at all times press the lug 59 of said lever toward said finger 57. The force exerted 85 by the spring may be varied by shifting it from one of the notches to another at a different distance from the fulcrum bolt.

As a result of this construction the spring 66 acts through the lever 58 to oppose the upward turning of the frame 39-40-41 about the rod 31, until such movement has so far progressed as to cause the lower end of the finger 57 to pass over the edge of the lug 59, after which it acts on said finger to assist 90 said upward movement. Obviously by shifting the bolt 61 in its slot 60, it is possible to vary at will the amount of upward swing of the frame 39-40-41 and therefore the diameter of the filled bobbin before the finger 100 passes over the lug 59 and it is automatically thrown up and out of action by the spring 66.

In order to evenly distribute the thread upon a bobbin mounted on the spindle 47, I reciprocate the rod 35 with the yarn guides 105 37, by means of any suitable device driven from the shaft 26. In the present instance this consists of a worm 68, fixed to said shaft and meshing with a worm wheel 69, mounted on a spindle 70 supported in bearings 71 110 projecting upwardly from the top plate 3 of the main frame. Said spindle also has fixed to it a cam 72 designed to coöperate with a pin 73 on one arm 74 of a lever whose second arm has fixed integral with or attached to it a weight 75 at all times acting to maintain said pin and cam in engagement. The arm 74 is formed with a longitudinally 115 extending slot 76 in which is adjustably clamped a headed pin 77, extending into the 120 longitudinal slot 78 of an arm 79 fixed to and extending downwardly from the reciprocating rod 35.

Under conditions of operation supply bobbins x' are mounted on the spindles 5 and 125 6 respectively and the latter are placed in the bearings 7, 8 and 9, as shown in Fig. 1. Thereafter suitable braking devices are applied to the bobbin and the end of the thread from the supply bobbin is run 130

through a tension device up around the porcelain or other guide 38 and thence through the yarn guide 37. An empty bobbin spool is placed on the spindle 47 while this is held 5 by its spring in an upwardly inclined position and power is applied to the main shaft 26 to turn the driving rollers 29 and 30. Each handle 46 is then pressed downwardly and at the same time given a limited 10 rotary movement which turns the spindle 44 so that the free end of the bobbin spindle is brought into engagement with the plate 52 immediately in front of the arm 39 and thereafter the frame 39-40-41 is swung 15 downwardly.

The inverted U-shaped piece 53 thereupon acts upon the free end of the bobbin spindle to force this rearwardly so that when the cylindrical surface of the bobbin finally 20 comes into engagement with the surface of the driving roll 29, said spindle end has been bent rearwardly sufficiently to enter the recess 51 in the arm 39. The end of the thread is now introduced between the bobbin 25 spool and the member 41, and the shaft 26 is turned in a direction such as to cause said thread to be at once drawn in between the driving pulley and said bobbin. Owing to the proximity of the bar 32 and also 30 to the upwardly flowing current of air between the bobbin and said bar caused by the rotation of the bobbin spool, this thread end is caused to turn upwardly between said parts and to thereafter be carried around between the bobbin and the driving roll so that 35 it is almost immediately held fast and thereafter wound on the bobbin as said roll continues to turn, being evenly distributed by the reciprocation of the rod 35 under the 40 action of the cam 72.

As the thread continues to be wound upon the bobbin it is obvious that its spindle 47 and hence the frame 39-40-41 is gradually moved away from the driving roll 29, turning around the rod 31 as an axis and moving the finger 57 up on the inclined lug 59 of the lever 58 until it finally passes over the sharp edge of said lug, whereupon the spring 66 acts through said lever and 45 the finger to continue the upward swing of said frame until the finger comes into engagement with a stop 80, projecting from the standard 24. Such upward movement of said frame allows the bobbin spindle 47 by reason of its tendency to occupy a position on the forward side of the recess 51 to move out of said recess so that the spring 48 becomes effective to rotate the spindle 44 and throw up the bobbin spindle with 50 the filled bobbin to the elevated position shown in dotted lines in Fig. 1. The thread is thereupon cut by being drawn against the knife blade 54 and the filled bobbin is replaced by an empty one, which is brought 55 into engagement with the driving roll and

supplied with thread as heretofore explained.

Each bobbin spindle has held to it by means of a set screw, a flanged head 82 having in its face a conical recess designed 70 for the reception of the end of the bobbin. Said recess preferably has a lining 83 of felt or the like, in order that it may serve to retard rotation of the bobbin on the spindle when the latter is thrown to its raised 75 position.

Obviously the amount of thread wound on a bobbin before the latter is automatically thrown up and out of engagement with the driving roll may be varied at will 80 by adjusting the position of the lever 58 to vary the length of the incline on the lug 59 to be moved over by the finger 57 before the latter can pass over its edge and cause the frame 39-40-41 to be thrown up. 85

It is to be noted that the ease of putting the machine in operation is materially increased by reason of the construction whereby a single downward and rotary movement of the bobbin controlling handle 90 46 suffices to place the bobbin in position to be filled.

Further, the automatic release and throwing up of the filled bobbin by reason of the peculiar mounting of the bobbin spindle so 95 that its free end tends to lie to one side of the recess 51, constitutes another valuable feature tending to facilitate the easy and consistent operation of the machine.

The provision of the conical lined bobbin-holding head on the spindle 47 assures the stopping of the rotation of the filled bobbin as soon as this is thrown up by reason of the friction exerted on said bobbin by the material in said head. 100 105

I claim:—

1. The combination in a bobbin winding machine of a driving roller; means for supporting a bobbin in frictional engagement with said roller consisting of a spindle pivotally mounted at one end to swing on an axis at right angles to its length; means tending to swing the spindle about its pivot away from the roller; and an automatically releasable catch normally holding the second end of the spindle down with the bobbin in engagement with said roller. 110 115

2. The combination in a bobbin winding machine of a frictional driving roller; a main frame; an oscillatory frame on said main frame; a bobbin spindle having one end pivotally supported on said oscillatory frame; a hook also mounted on the oscillatory frame in position to engage the second end of said spindle; and means for automatically releasing the second end of the spindle from the hook when a predetermined amount of thread has been wound on the bobbin. 120 125

3. The combination in a bobbin winding 130

- machine of a frictional driving roller; a main frame; an oscillatory frame thereon; a spindle retaining hook on the latter frame; a bobbin spindle mounted on the frame and tending to occupy a position to one side of the line of the hook recess when a bobbin on the spindle engages the roller; and a spring tending to turn the spindle upwardly on its pivot.
- 10 4. The combination in a bobbin winding machine of a frictional driving roller; a main frame; an oscillatory frame thereon; a spindle retaining hook on the latter frame; a bobbin spindle mounted on the frame and tending to occupy a position to one side of the line of the hook recess when a bobbin on the spindle engages the roller; a spring tending to turn the spindle upwardly on its pivot; with means for automatically causing the release of the spindle from the hook to permit action of said spring.
- 15 5. The combination in a bobbin winding machine of a frictional driving roller; a main frame; an oscillatory frame on said main frame; a pivotally mounted spindle and a spindle retaining hook on said oscillatory frame; a device for opposing movement of the oscillatory frame and spindle away from the roller for a predetermined distance and thereafter aiding said movement; and means for automatically releasing the spindle from the hook when the oscillatory frame has reached a point at which its movement away from the roller is aided by said device.
- 20 6. The combination in a bobbin winding machine of a frictional driving roller; a main frame; an oscillatory frame on said main frame; a pivotally mounted spindle and a spindle retaining hook on said oscillatory frame; a device for opposing movement of the oscillatory frame and spindle away from the roller for a predetermined distance and thereafter aiding said movement; with means for automatically releasing and throwing up the spindle from the hook when the oscillatory frame has reached a point at which its movement away from the roller is aided by said device.
- 25 7. The combination in a bobbin winding machine of a frictional driving roller; a main frame; an oscillatory frame mounted thereon; a pivotally mounted spindle and a spindle retaining hook on said latter frame; a device for directing the free end of the spindle into the recess of the hook as the oscillatory frame is moved to bring a bobbin into engagement with the roller; with means for automatically releasing the spindle from said hook and throwing it up when a predetermined amount of thread has been wound on the bobbin.
- 30 8. The combination in a bobbin winding machine of a frictional driving roller; a main frame; an oscillatory frame mounted
- thereon; a pivotally mounted spindle and a spindle retaining hook on said latter frame; a guide on the main frame placed to engage the free end of the spindle as it with the oscillatory frame is moved down to guide said end into the hook; with means for automatically releasing and throwing up the free end of the spindle when a predetermined amount of thread has been wound on the bobbin thereon.
- 35 9. The combination in a bobbin winding machine of a frictional driving roller; a main frame; an oscillatory frame mounted thereon; a pivotally mounted spindle and a spindle retaining hook on said latter frame; a guide on the main frame placed to engage the free end of the spindle as it with the oscillatory frame is moved down to guide said end into a hook; means for automatically releasing and throwing up the free end of the spindle when a predetermined amount of thread has been wound on the bobbin thereon; with a device for limiting the downward movement of the free end of the spindle prior to its entry into the recess of the hook.
- 40 10. The combination in a bobbin winding machine of a frictional driving roller; a main frame; an oscillatory frame mounted thereon; a pivotally mounted spindle and a spindle retaining hook on said latter frame; a guide on the main frame placed to engage the free end of the spindle as it with the oscillatory frame is moved down to guide said end into the hook; means for automatically releasing and throwing up the free end of the spindle when a predetermined amount of thread has been wound on the bobbin thereon; with a projecting finger carried by the oscillatory frame for limiting the downward movement of the free end of the spindle prior to its entry into the recess of the hook.
- 45 11. The combination in a bobbin winding machine of a main frame; a frictional driving roller; an oscillatory frame on said main frame; a spindle-retaining hook and a bobbin spindle thereon; a spring tending to throw said spindle into an upwardly inclined position; a guide on the main frame mounted to direct the free end of the spindle into the hook as the oscillatory frame is moved toward the driving roller; a projecting member on the oscillatory frame placed to retain the free end of the spindle in a position adjacent the hook prior to its entry therein; and a handle for moving the oscillatory frame.
- 50 12. The combination in a bobbin winding machine of a frictional driving roll; a pivotally mounted bobbin spindle; means for retaining said spindle in position with a bobbin thereon in driving engagement with the roll; means tending to move the spindle into an elevated position; a device for au-

tomatically releasing said spindle from said retaining means; and a structure on the spindle frictionally engaging the bobbin when the spindle is elevated for retarding movement thereof but substantially inoperative when the bobbin is in driving engagement with the roll.

13. The combination in a bobbin winding machine of a frictional driving roll; a pivotally mounted bobbin spindle; means for retaining said spindle in position with a bobbin thereon in driving engagement with

the roll; means tending to move the spindle into an elevated position; a device for automatically releasing said spindle from said holding means; and a collar on the spindle having a lining frictionally engaged by the end of the bobbin under the action of gravity to retard rotation thereof after the spindle has been moved to its elevated position.

In witness whereof I affix my signature.

ALFRED F. McCOLLUM.
